CLAIM

We claim the ornamental design for a portable electronic device, as shown and described.

DESCRIPTION

FIG. 1 is a front perspective view of a portable electronic device showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof; and,
FIG. 8 is a rear perspective view thereof.

The dash-dot broken line, and the dot-dot broken lines shown in the figures that are immediately adjacent to the shaded areas and define unshaded regions, represent the bounds of the claim. All other dot-dot broken lines, including the top and rear of the portable electronic device, and the broken lines on the front surface to the right of the speaker, are directed to portions of the portable electronic device. The broken lines form no part of the claimed design.
